FIG. 3

FIG. 5.

UNITED STATES PATENT OFFICE.

HENRY PRICE BALL, OF NEW YORK, N. Y., ASSIGNOR TO GENERAL INCANDESCENT ARC LIGHT COMPANY, OF NEW YORK, A CORPORATION.

AUTOMATIC CIRCUIT-BREAKER.

No. 897,858.

Specification of Letters Patent.

Patented Sept. 1, 1908.

Application filed January 31, 1903. Serial No. 141,319.

To all whom it may concern:

Be it known that I, HENRY PRICE BALL, a citizen of the United States, residing at New York city, county and State of New York, have invented certain new and useful Improvements in Automatic Circuit-Breakers, of which the following is a specification.

My invention relates to circuit breakers of the type adapted to be used in connection with an oil switch or other switching apparatus and to be actuated by an over-load in the circuit in which it is included.

The object of my invention is primarily to provide means whereby the circuit breaker mechanism cannot be deliberately held closed against an over-load or short circuit; and secondarily, to provide a construction whereby the hand-lever through which the switch mechanism is actuated to close the circuit, will not be moved when the switch is actuated to break the circuit, thereby preventing possibility of injury to a person passing the switch-board, by the sudden outward and downward movement of the hand lever when the switch opens, as is now the case with the major portion of the circuit breaker mechanisms which have heretofore been constructed.

The accompanying drawings will serve to illustrate my invention.

Figure 1 is a side elevation showing my improved actuating mechanism, mounted on the front of a switch board and connected to an oil switch, which is shown partially in section, mounted on the back of the switch-board. This view also showing in diagram, the circuit connections between the generator of a three phase distribution system, an over-load device, and circuit breaker. Fig. 2 is a similar view with the upper part of the switch-board in section, and showing the hand-lever at right angles to the switch-board and in the position which it would occupy preparatory to closing the switch. Fig. 3 is a front view of the actuating mechanism with the hand lever in the upper position. Fig. 4 is a section and plan view on the line X X of Fig. 3. Fig. 5 is a section and plan view on the line Y Y of Fig. 3.

Similar numerals indicate like parts.

In the drawings, 10 indicates a switch-board. Mounted on the front of the switch-board is a plate 11, from about the center of which projects the horizontal bearings 12. Mounted and secured in these bearings is a

horizontal shaft 13, on which is pivotally mounted the hand-lever 14. This hand-lever consists of a handle 15, and the side plates 16. Mounted on the shaft 13 between the side plates 16 of the hand-lever is a second lever 17, which consists of a hub portion 18, upwardly extending bifurcated portion 19 and two downwardly extending portions 20 having the shape of a sector, as shown in Fig. 2. Projecting outwardly from the sector portions 20 are the horizontal pins 21. Arranged over the hub portion 18 are the coiled springs 22. The opposing ends of each spring 22 include between them a pin 21, and also a projection 23, extending from the front of plate 11, as is shown in Fig. 2. The object of these springs is to impart an upward or downward movement to the lever 17, depending upon the position into which it has been moved by the handle 15, and through the lever 17, a horizontal movement to the connecting rod 24, pivoted to the sector portion 20 of the lever 17, and to the connecting rod 25 pivotally connected to the rod 24, and a rocking motion to the switch blade 26 of the oil well 27, when the circuit breaker is actuated under the influence of an over-load. It will be seen by reference to Figs. 1, 2 and 3, that the springs 22 will exert an active pressure and irrespective of whether the hand-lever is in the position shown in Fig. 1 or Fig. 3.

In order to engage the lever 17 with the hand-lever 14, to move this lever to either the top or bottom position, as shown respectively in Figs. 3 and 1, the bifurcated end 19 of the lever 17 is rounded and has formed in it a concave slot 28. This slot 28 is adapted to engage with a horizontally disposed latch pin 29, carried in arms 30, pivotally secured in bearings 31, Fig. 5, projecting backward from the arms 16 of the hand-lever 14. Situated over the pin 29 is a spring 32, which normally presses the pin downward, and in contact with a pin 31^a arranged transversely of the lever 17. It will be seen that when the hand lever 14 is moved over the lever 17, that the pin 29 will engage in the slot 28, of such lever, and further, that when said levers 14 and 17 are in engagement that any movement of the lever 14 upward or downward will carry with it the lever 17 and hence effect longitudinal movement of the connecting rods 24 25, and reciprocate switch blade 26 of the oil switch 27, thereby throwing such

switch blade into engagement with one or the other of the spring contacts 26^a, 26^b, of the oil switch 27 or into the central position, indicated by the dotted lines 26^c.

5 In order to hold the lever 14 either in the top or bottom position, I provide the latches 33. These latches are adapted to engage with a pin 34, arranged transversely of the side plates 16 near to the handle 15 as shown 10 in Fig. 3. These latches are spring pressed through the springs 35 and are provided with handles 36 through which they may be moved to release the hand lever 14.

15 In order to release the lever 17 from engagement with the hand-lever 14, upon the occurrence of an over-load, I provide the device which I will now describe. Mounted on the plate 11, at the right of the lever 17, is a solenoidal magnet 37. Arranged to have an 20 upward movement in this magnet is a core, 38, the upper end of which is formed as a pin 39, adapted to move through an opening in a plate 40, as shown in Fig. 5. Pivotaly mounted on the plate 40 is a lever 41, on the 25 outer end of which is a handle 42, which may be moved to release the latch and open the circuit breaker when desired. Connected to the rear end of this lever is a link 43, provided with an elongated slot 44, in its upper end, 30 and connected through this slot with an arm 45 secured to sleeve 46, mounted on shaft 47, which has its bearings at 48, 49, on the front of plate 11. Pivotaly mounted on shaft 47, but secured to and adapted to be moved 35 when the sleeve 46 is moved, is an arm 50, which extends horizontally forward and downward and has its outer end shaped to form an inclined plane. Located under this arm is a spring 51, which normally tends to 40 lift the arm. Pivotaly connected to a projection 52 from the sleeve 46 is a link 53, which is carried downward and pivotaly connected to one side of a bar 54, (Fig. 1), pivoted at 55 to one of the bearings 12. 45 Pivotaly connected to the opposite end of the bar 54 is another link 56, which is pivotaly connected to an arm 57, pivoted to the front plate at 58. Over this arm is a spring 59, which tends to press the arm 57 down- 50 wardly. The arm 57 is shaped on its under side to form an inclined plane.

Having reference to Figs. 1, 3 and 5, it will be seen that when the hand-lever 14 is in the top position, the arm 50 lies under the pin 29, 55 and when the parts are in the position shown in Fig. 1, the arm 57 lies over the pin 29. It will be readily understood that when an excessive current of electricity is sent through the solenoid 37, it will lift its core, which, im- 60 pinging upon lever 41, will raise the lever 41 and through the interposed links and levers, raise the arm 50 and depress the arm 57, one of which, acting upon the latch pin 29, will raise or lower it depending upon whether the 65 parts are in the position shown in Figs. 3

or 1, and release the lever 17 and permit the springs 22 to exert the required tension to operate the switch to break the circuit and bring the lever 17 into the position shown in the dotted lines Fig. 1.

70 In the diagram, Fig. 1, I have shown a preferred means for connecting the circuit breaker in circuit with a three phase generator, and an over-load device. In this diagram, 60 indicates a three phase generator; 75 61, a series transformer; 62, an over-load device. The primary of the transformer, 63, is connected through conductor 64 with one terminal of dynamo 60 and with the center terminal 27^a of the oil switch 27. The secondary, 65, of the transformer 61, is connected through one terminal 66 to one terminal of solenoid 37 and through the other terminal 67 to one terminal of solenoid of over-load device 62, and one terminal of this 80 over-load device through conductor 68 to the opposite terminal of solenoid 37. On the 85 ends of the conductors 66 and 68 are the contacts 69, 70. 71 indicates the core of the over-load device. This core carries a bridge-piece 72, adapted to coact with the contacts 69, 70, to form a shunt through which the 90 current of the secondary of the transformer 61 is normally transmitted around the magnet 37.

95 The operation of the device as a whole, is as follows: When the oil switch is open, the parts will assume the position shown in the dotted lines, Fig. 1. To close the switch the hand lever 14 is moved upward until the 100 latch carried by it engages with the lever 17. The levers 14 and 17 are then moved either upward or downward, as is desired, to close the circuit through the contact 26^a or 26^b of the oil switch. Should now, the current 105 transmitted through the primary of the transformer 61, exceed a predetermined amount, a corresponding current will be excited in the secondary of the transformer, which will 110 energize the magnet of the over-load device 62, which will raise its core, and lift the bridge-piece 72 off of the contacts 69, 70, and allow the current to pass by conductors 68, 66, through the solenoid 37, thereby energizing the solenoid which, acting upon its core, 115 will release the lever 17 from engagement with the lever 14, permitting it to return to its original position, *i. e.*, that shown in dotted lines, Fig. 1, and without effecting any movement of the hand lever 14.

120 Having thus described my invention, I claim:

1. A double-throw electric switch biased to open when closed and having its open position between two closed positions, an 125 operating lever therefor, and means for automatically feeding the movable switch element from either of its closed positions.

2. A double-throw electric switch biased to open when closed and having its open 130

position between its two closed positions; an operating lever therefor, and an electrically-actuated means responsive to predetermined electrical conditions in its circuit to free the 5 movable switch element from either of its closed positions.

3. A double-throw switch having fixed contacts, a movable contact coöperating therewith and having a neutral position between said fixed contacts, an operating lever, a detachable connection between said lever and the movable contact, and an electro-responsive device for breaking said connection.

4. An electric switch comprising a movable switch element having a plurality of closed positions, an operating lever therefor, an independently mounted rocking member adjacent to said lever and connected to the movable switch element, means for connecting said member to said lever, and means for automatically breaking said connection when the switch is in any of its closed positions.

5. An electric switch comprising a movable switch element having a plurality of closed positions, an operating lever therefor, an independently mounted rocking member adjacent to said lever and connected to the movable switch element, an electrically controlled connection between said member and said lever, and means for breaking said connection when the switch is in any of its closed positions.

6. An electric switch comprising a movable switch element having a plurality of closed positions, an operating lever and a rocking member concentrically mounted and independently movable, said member being connected to said element, a connection between said member and said lever, and automatic means for breaking said connection when the switch is in any of its closed positions.

7. An electric switch comprising a support, a movable switch element having a plurality of closed positions, an operating lever, a rocking member connected to said element, a connection between said member and said lever, and automatic means comprising co-operating elements carried by said member and support for breaking said connection when the switch is in any of its closed positions.

8. An electric switch comprising a support, a movable switch element having a plurality of closed positions, an operating lever and a rocking member concentrically mounted and independently movable, said member being connected to said element, a connection between said member and said lever, and automatic means comprising co-operating elements carried by said member and support for breaking said connection when the switch is in any of its closed positions.

9. A double-throw electric switch comprising fixed contacts, a movable contact co-

operating therewith and biased to a neutral position between said fixed contacts, an operating lever therefor, a connection between said lever and said movable element, means for breaking said connection, and a fixed electrically energized coil for actuating said breaking means.

10. A double-throw electric switch comprising fixed contacts, a movable contact co-operating therewith and biased to a neutral position between said fixed contacts, an operating lever therefor, a connection between said lever and said movable element, and a single electrically actuated tripping mechanism for breaking said connection when the switch is in either of its closed positions.

11. An electric switch comprising fixed contacts, a movable contact coöperating therewith and biased to a neutral position between said fixed contacts, a movable member connected to said movable contact, a movable operating lever adjacent to said movable member, and latching means between said movable member and said lever whereby said lever is latched to said movable member whenever said member and lever assume a predetermined relation.

12. In a double-throw electric switch, the combination of a movable switch element, a movable member connected to said element and adapted to occupy a mid-position corresponding to the open position of said switch, an operating lever pivoted adjacent to said movable member, and latching means between said movable member and said lever whereby said lever is latched to said movable member whenever it is moved into said mid-position.

13. A double-throw electric switch biased to open when closed and having its open position between two closed positions, a pivoted hand-lever, a latch carried thereby, a second pivoted lever engaged by the latch on the hand-lever, said levers being movable from a circuit-closing position below their pivotal point to a circuit-closing position above their pivotal point, a switch-blade, a connecting rod between said second named lever and said switch-blade, and means for releasing said second named lever from engagement with said first named lever upon the occurrence of abnormal current in the circuit.

14. A double-throw electric switch comprising fixed contacts, a switch-blade having a neutral position between said contacts, a pivoted lever movable from a circuit-closing position below its pivotal point to a circuit-closing position above its pivotal point, a connecting-rod between said lever and said switch-blade, means for moving said lever to different circuit-closing positions, and means for exerting spring pressure upon said lever when moved to circuit-closing position, and means for releasing said lever upon overload.

15. A circuit-breaker having its open position between its closed positions and biased to open when closed, comprising a hand-operated member, a circuit controlling member, a latch carried by said hand-operated member and coacting with said circuit controlling member, latches engaging with said hand-operated member to hold it in different circuit-closing positions, an electro-responsive device, and means actuated by the electro-responsive device for releasing said circuit controlling member from engagement with said hand-operated member upon the occurrence of abnormal current in the circuit. 70
15. 16. A circuit-breaker comprising two levers adapted to be coincidentally moved from the horizontal plane occupied by their pivotal point to a vertical plane above or below the pivotal point, means whereby the motion imparted to one lever will be communicated to the other, means for holding said levers in either of said vertical planes, and electro-responsive means adapted to release one of said levers upon the occurrence 75 of abnormal current in the circuit.
15. 17. In an electric switch, fixed contacts, a movable contact coöperating therewith and having a neutral position between said fixed contacts, a pivoted hand-lever, a latch carried thereby, a second pivoted lever engaged by said latch on the first named lever, said levers adapted to be coincidentally moved from the horizontal plane of their pivotal points to vertical planes above or below the pivotal points, connections between said second lever and said movable contact, means put under tension by the movement of the second named lever, and electro-responsive means for releasing said latch and permitting 80 movement of the second named lever away from the first named lever.
15. 18. In an electric switch, fixed contacts, a movable contact coöperating therewith and having a neutral position between said fixed contacts, a hand-lever, a second lever moved by the hand-lever up or down from its normal horizontal position to a circuit-closing position above or below the pivotal point of said lever, an electro-responsive device, and means interposed between said electro-responsive device and said second named lever and acting to release said lever to permit the switch to open without moving the hand-lever. 85
15. 19. In an electric switch, fixed contacts, a movable contact coöperating therewith and having a neutral position between said fixed contacts, a pivoted member connected to said movable contact, a spring put under tension by the movement of said movable contact away from neutral position, means for moving said member to different circuit-closing positions, latches for holding said member in said circuit-closing positions, and electro-responsive means for releasing said member and permitting said spring to act. 90
20. In an electric switch, fixed contacts, a movable contact coöperating therewith and having a neutral position between said fixed contacts, a lever, a spring put under tension by the movement of the lever, a hand-lever for holding said lever in circuit-closing position above or below its pivotal point, means for holding said lever and said hand-lever in said circuit-closing positions, and means for releasing said lever and allowing said spring to exert its pressure. 95
21. In a double-throw electric switch having its open position between two closed positions, a pivoted spring-actuated lever tending to assume a circuit-opening position, means for moving said lever into circuit-closing positions above or below its pivotal point, a latch coacting with said lever to retain it in circuit-closing position, and electro-responsive means to actuate said latch and release said lever. 100
22. In a double-throw electric switch biased to open when closed and having its open position between two closed positions, a pivoted hand-lever, a second pivoted lever, said levers movable into two circuit-closing positions, means carried by the hand-lever for engaging the second lever, an electro-responsive device, and means actuated by the electro-responsive device to release the two levers from engagement. 105
23. In a double-throw electric switch biased to open when closed and having its open position between two closed positions, a pivoted hand-lever, a second pivoted lever, said levers capable of being moved from a circuit-closing position below their pivotal point to a circuit-closing position above their pivotal point, means for holding said levers in said position above or below their pivotal point, means for holding said levers in engagement, an electro-responsive device, and means actuated by the electro-responsive device to release the two levers from engagement. 110
24. The combination with a double-throw switch biased to open when closed and having its open position between two closed positions, of an operating handle therefor, and electrically controlled means for opening said switch independently of the handle. 115
25. The combination of a double-throw switch biased to open when closed and having its open position between two closed positions, a handle for said switch, and means responsive to a variation of current in the circuit controlled by said switch for opening said switch independently of said handle. 120
